BOBBIN RELEASE FOR WEFT REPLENISHING MECHANISM

William A. Blanchard, Millbury, Mass., assignor to Crompton & Knowles Loom Works, Worcester, Mass., a corporation of Massachusetts

Application April 3, 1950, Serial No. 153,675

12 Claims. (Cl. 139—232)

1

This invention relates to improvements in weft replenishing mechanisms more particularly of the multicolor type and it is the general object of the invention to provide an improved bobbin releaser for such mechanisms.

The usual multicolor weft replenishing mechanism employs so-called bobbin cradles at the bottoms of the stacks of reserve bobbins. These cradles are normally empty but when a weft replenishing operation is called involving any particular color the corresponding cradle is rocked first in one direction to receive the bottom bobbin of the superposed stack of bobbins while the shuttle is at the magazine or replenishing end of the loom. At a later time when the depleted shuttle is about to return to the replenishing end of the loom the cradle is given a reverse rocking motion to discharge its bobbin, whereupon the latter moves to a transfer position from which it is inserted into the shuttle.

The rocking of the cradles is effected by means of releasers mounted for vertical sliding motion on the replenishing mechanism. A rocking color slide ordinarily effects upward motion of a releaser to produce the first of the previously mentioned rocking motions of the cradle, and thereafter lowers the releaser to its normal position for the purpose of effecting the second of the previously mentioned rocking motions of the cradles. When descending the releasers act by means of dogs on their upper ends to set the magazine for bobbin transfer. Each releaser has two vertically spaced lugs for engagement with the color slide, and in a four-color magazine the lugs of the two inner releasers align with the latter, but the lugs of the front and back releasers are offset. Furthermore, the lower ends of the releasers have cam slots for cooperation with their cradles, and these cam slots are formed in wings or the like two of which are disposed to the right and the other two of which are disposed to the left of their respective releasers. It has been customary in the past to make four of these releasers for a four color weft replenishing mechanism, all four releasers being different and each requiring its own pattern and machining operations.

It is an important object of the present invention to provide releasers made in such manner that a minimum number of parts are required for producing the various types required in the multicolor weft replenishing mechanism.

One feature of the invention is that the releaser is made of laminations having perforations to receive tongues or tangs on the offset lugs for

2

the color slide. These tongues assist in holding the laminations together. Another feature is that only two types of lugs are required to perform the function of the four lugs of the front and back releasers.

It is another object of the invention to make releasers with reversible wings formed with the aforesaid cam slots, these wings being preferably flat so that when applied to the bottoms of the releasers they can extend either to the right or the left, as desired.

It is still another object of the invention to form the lower ends of the releasers with cavities or the like to receive the upper parts of the aforesaid wings. These cavities may be provided by notches in the intermediate laminations between support lugs on the outer laminations.

It is a still further object of the invention to make the aforesaid dogs of sheet metal having curved arms to inclose part of a metallic cup for a compression spring which acts on the dog.

With these and other objects in view which will appear as the description proceeds, the invention resides in the combination and arrangement of parts hereinafter described and set forth.

In the accompanying drawings, wherein a convenient embodiment of the invention is set forth,

Fig. 1 is a side elevation of a multicolor weft replenishing mechanism having the invention applied thereto, the releasers being shown in their normal down position,

Fig. 2 is a vertical section on an enlarged scale on line 2—2, Fig. 1,

Fig. 3 is an enlarged detail transverse section through the upper part of one of the releasers and the associated dog on line 3—3, Fig. 2,

Fig. 4 is an enlarged detail horizontal section on line 4—4, Fig. 1, showing part of one of the releasers and the cradle operating wing associated therewith,

Fig. 5 is an enlarged transverse section on line 5—5, Fig. 2,

Figs. 6 and 7 are a plan and a front elevation, respectively, of one of the offset lugs used for the front and back releasers,

Figs. 8 and 9 are side and front elevations, respectively, of the wing member which is applicable to the bottoms of all of the releasers,

Figs. 10 and 11 are rear and side elevations, respectively, of one of the outer laminations for the front and back releasers,

Fig. 12 is a fragmentary rear elevation of the lower end of an intermediate lamination used with the longer releasers,

Figs. 13 and 14 are similar to Figs. 10 and 11, but show one of the shorter releasers,

Fig. 15 is similar to Fig. 12 but shows part of an intermediate lamination for the short releaser,

Fig. 16 is a perspective view of the rearmost releaser,

Fig. 17 is a perspective view of one of the short releasers,

Fig. 18 is a fragmentary perspective view of the lower end of an assembly of laminations for one releaser before the wing is applied, and

Fig. 19 is a diagrammatic view showing the disposition of the wings which operate the cradles for all four of the releasers and indicating how only two types of offset lugs can be used to provide the four lugs for the long front and back releasers.

Referring particularly to Fig. 1, the loom frame 1 supports a multicolor weft replenishing mechanism M having a color slide 2 slidable horizontally and rockable angularly thereon. The color slide includes a shaft 3, see Fig. 2, and has front and back releaser operating fingers 4 and 5. By means of a rod 6 the color slide 2 and shaft 3 are given a clockwise rocking movement as viewed in Fig. 2 whenever the shuttle S is at the replenishing end of the loom and indicates weft exhaustion through detector mechanism indicated at D. At a later time the color slide and shaft are rocked in an opposite direction for the purpose of releasing a bobbin and permitting it to move to the transfer position indicated in dotted lines at T, Fig. 1.

The magazine has cradles for controlling the bobbins which are arranged in vertical stacks but not shown in Fig. 1. These cradles, from front to back, are designated in Fig. 1 at 7, 8, 9 and 10, and are associated respectively with releasers R1, R2, R3 and R4 mounted for vertical sliding on a frame plate 11 forming part of magazine M. Whenever a releaser is raised by the color slide the corresponding cradle rocks to receive a bobbin, and when the releaser is later depressed the cradle rocks oppositely to discharge its bobbin.

The magazine is provided in the upper part thereof with a setting shaft 12 to which is secured an operating or setting bar 13. The shaft and bar are ordinarily at rest and will not be moved by upward motion of any of the releasers, but when a releaser is depressed the bar 13 will be engaged by one or another of the dogs D1, D2, D3 or D4 on the upper ends of the releasers, and will be rocked in a counter-clockwise direction, Fig. 2, to set the magazine for a replenishing operation. Each releaser has a wedge 14 intermediate top and bottom notches 15 and 16 which receive one at a time a yielding lock plunger 17 the purpose of which is to hold the releaser either in predetermined raised or lowered position.

The matter thus far described is of common construction and operates in the usual manner except for the particular form of releasers R1-R4 and dogs D1-D4. In the past the releasers have been made in one piece, generally in the form of a casting, and it has been necessary to have four different releasers requiring four different patterns and machining operations. The front and back releasers R1 and R4 are relatively long, while the intermediate releasers R2 and R3 are shorter.

In carrying the present invention into effect the releasers are preferably made of thin elongated laminations which are preferably bonded together, as by copper. Each releaser has a cradle operating wing secured to the lower end thereof,

and has a dog pivoted to the upper end thereof. In addition the front and back releasers are provided with offset lugs having shanks or tangs which extend through and assist in holding the laminations together, while the intermediate releasers have lugs formed integral with the laminations. One of the longer releasers will be described in detail, after which one of the short releasers will be described.

Referring more particularly to Fig. 16, the releaser R4 has an elongated body 30 thereof made in the present instance of five thin sheet metal parallel laminations. The right and left outside laminations are indicated at 31 and 32, and the three intermediate laminations are indicated at 33, 34 and 35, see Figure 4. All of the laminations 31-35 have their upper ends formed with an offset head 36 and are provided with perforations 37 which receive the pivot pin 38 of dog D4.

The latter dog is preferably made of sheet metal and has an operating pawl-like body or member 40 formed with side arms 41 and 42. As shown in Fig. 5 these arms have their free ends curved toward each other as at 43 to partly enclose a metallic cup 44 welded, brazed, or otherwise secured to the bent arms 43. This cup is preferably made cylindrical with a solid bottom 45 to receive the down thrust of a compression spring 46 the upper end of which is received in a pocket 47 in head 36 which may be formed in the intermediate laminations 33-35 between the side laminations 31 and 32.

The effect of the spring is to tend to turn the dog D4 in a counter-clockwise direction as viewed in Fig. 2. When the releaser is in down position the bottom 45 of the cup will engage plate 11 of the magazine so that the pawl 40 will be held spaced from the bar 13. When the releaser is raised the cup rises above plate 11 and the spring thereupon rocks the dog so that its pawl 40 overhangs the bar 13. Thereafter by the downward motion of the releaser the dog engages the bar 13 to rock the shaft 12. All of the dogs D1-D4 may be similar to the one described in connection with Fig. 2.

The lower end of releaser R4 is provided with the wing W4 which, as shown more particularly in Fig. 8, is provided with a flat body 55 having a bobbin cradle actuating slot 56 formed therein and disposed largely at one side thereof. Extending upwardly from body 55 is a neck or arm 57 formed at the top thereof with a transverse head 58. In the particular form of the invention set forth the head 58 will have a width corresponding to five times the thickness of a single lamination and the neck 57 will have a width corresponding to the thickness of three of the laminations.

As shown in Fig. 10, which shows one of the two side laminations of releaser R4, the lower end of the outer lamination 32 is provided with a notch or slot 60 having a depth equal to the thickness of the neck 57 and head 58. The bottom of the lamination has a second notch 61 to receive the upper part of body 55. Extending between the notches 60 and 61 is a guide lug 62. The lower ends of each of the intermediate laminations are formed with a single elongated notch 63 preferably of the same depth as the notches 60 and 61, see Fig. 12.

All of the laminations will be provided with upper and lower slots or perforations 65 and 66, respectively, elongated in the direction of the length of body 30, the upper laminations being in alignment and the lower perforations likewise

being in alignment. The upper offset lug 67 in high position may be formed for instance as shown in Figs. 6 and 7 from a bent piece of sheet metal having a lifting finger 68 bent at right angles to a lateral arm 69 from which projects a tongue or tang 70. As indicated in Fig. 7 the tang 70 is of less height than the arm 69 to form shoulders 71. Lug 67 has a top downwardly inclined beveled edge 72 and a horizontal lower edge 73.

The bottom lug 75 in low position on the releaser is similar to lug 67, but of the opposite hand and has a beveled lower edge 76 and a horizontal top edge 77 on a lifter finger 78. Lug 75 has an arm 79 similar to arm 69 and has a tang 80 like tang 70, see Fig. 16.

When assembling the parts the laminations will first be arranged with the perforations 65 aligning and the lower perforations 66 also aligning. The tang 70 of the top lug 67 will then be inserted into the aligned perforations 65 until the shoulders 71 engage the side laminations 31. The tang is of such length as to extend through all of the laminations and is of a shape to have a snug fit in perforations 65. Thereafter, the lower lug 75 is similarly fitted with its tongue extended through the aligned perforations 66.

The wing W4 is then applied to the lower end of the assembled laminations with its head 58 entering the notches 60 of the side laminations and extending along the tops of the notches 63 of the intermediate laminations. To form the releaser R4 the wing will be disposed to the left of the elongated body 30. When the wing is in this position the neck 57 will extend along and between the guide lugs 62 of the side laminations and the upper part of the body 55 will be in the notches 61 of the side laminations and will extend across the lower ends of the notches 63 of the intermediate laminations. If desired, the lugs 62 may be peened or otherwise deformed to hold the neck 57 and head 58 in position. The space between lugs 62 for the neck is shown at 81 in Fig. 18 and the space for head 58 is indicated at 59, and these spaces together form a T-shaped recess for the neck and head which is symmetrical about a line running lengthwise of the releaser.

The assembled parts are then put in a furnace so that all of the parts may be united, as by copper brazing, to form an integrated releaser. This bonding operation secures the laminations together, holds the tongues 70 and 80 to the laminations and assists the tongues to hold the laminations together, and also brazes the neck 57 and head 58 to the lower ends of the laminations.

The front releaser R1 will be made similarly to releaser R4, but with the lugs 67 and 75 disposed at the left, Fig. 1, and with wing W1 reversed, or at the right.

Referring particularly to Fig. 17 which shows short releaser R2 it will be noted that the side laminations 82 and 83, and the intermediate laminations 84, have top and bottom lugs 85 and 86 integral therewith and in the planes of the laminations. During the brazing operation the several aligned lugs will be secured to each other. In other respects the releaser R2 will be similar to the releaser R4 except that ordinarily it will be shorter. Releaser R3 will be similar to releaser R2 except that the wing W3 is disposed to the right.

It will be noted that the wings W2 and W4 of the releasers R2 and R4 extend to the left of the elongated body 30 of the releaser. When it

is desired for instance to make releaser R3 which has its wing W3 disposed at the right of the elongated body the wing will be turned over during assembly so that the slot 56 will be at the right instead of at the left. The two releasers R2 and R3 will be alike except for the right and left hand relationship of their wings. All the wings are alike and may be made as a flat sheet metal stamping.

Fig. 19 indicates diagrammatically how it is possible to use only two forms or types of offset lugs to form the four lugs required for the two releasers R1 and R4. As shown at the left of Fig. 19, the lugs 67 and 75 are disposed as shown in Fig. 16 to form releaser R4. When it is desired to use similar lugs to form the releaser R1, the top releaser 67 can be inverted and then have its tang inserted from the left into the perforations 66 to form a bottom lug 67A indicated in dotted lines, Fig. 19. Similarly, the top lug 75A of the releaser R1 will be made by reversing a bottom lug 75 and then inserting its tang from the left into the perforations 65 of releaser R1. By this inversion the beveled edges 72 and 76 will be on the outer side of the space 90 between the lugs, see Fig. 16, provided for the associated finger 4 or 5 of the color slide 2. The lower part of Fig. 19 indicates how the wings W1-W4 can be disposed to adapt them to the several releasers.

From the foregoing it will be seen that the invention sets forth a cheap but durable form of bobbin releaser made of a plurality of thin sheet metal laminations assembled to form the spaces 81 and 59 for the neck and head of a bobbin cradle operating wing. The laminations and the wing are bonded together, as by a brazing operation. It will also be seen that the outer laminations 31 and 32 are provided with guide lugs 62 for the neck 57 of the wing, while the intermediate laminations are provided with the elongated notches 63 along which the neck extends. A single type of wing can be used for all of the releasers, the wing in certain instances being disposed at the left and in other instances at the right. The front and back releasers are made with two types of offset lugs having tongues which extend through and assist in binding together the several laminations of the releaser. To form the releaser R4 for instance the lugs 67 and 75 will be disposed as shown in Fig. 16, but in forming the releaser R1 the lugs will be inverted and their positions interchanged and their tongues inserted from the left side, as suggested in Fig. 19. The dogs D1-D4 are each made of a piece of sheet metal having wings which are around and partly inclose a cup which receives the lower end of the comparison spring 46.

Having thus described the invention it will be seen that changes and modifications of the foregoing specific disclosure may be made without departing from the spirit and scope of the invention.

What is claimed as new is:

- 65 1. In a bobbin releaser for a weft replenishing mechanism operating with a cradle, a plurality of parallel elongated sheet metal laminations arranged side by side and secured together, the outer laminations having guide lugs and the inner laminations having notches between the lugs, and a cradle operating wing having a part extending into said notches between said lugs and secured to said laminations.
- 70 2. In a bobbin releaser for a weft replenishing mechanism operating with a cradle, a plurality

of elongated sheet metal releaser body forming laminations secured together, certain of said laminations being at the sides of the releaser and the other laminations being intermediate the side laminations, the intermediate laminations having notches at one end thereof and the side laminations projecting along said notches to define a recess, and a cradle operating wing having a part thereof extending into said recess and secured to said laminations.

3. In a bobbin releaser for a weft replenishing mechanism operating with a cradle, a plurality of elongated sheet metal body forming parallel laminations including side laminations and intermediate laminations between the side laminations, notches being formed at one end of the intermediate laminations, lugs formed on the corresponding ends of the side laminations defining a recess with said notches, a cradle operating wing formed with a neck extending into said recess, and bonding metal integrating said laminations, wing and neck.

4. In a bobbin releaser for a weft replenishing mechanism operating with a cradle, a plurality of elongated sheet metal parallel body forming laminations secured together including side laminations and intermediate laminations between the side laminations, adjacent ends of the intermediate laminations being formed with notches, notches being formed in said side laminations communicating with part of the notches in the intermediate laminations, and a cradle operating wing secured to said laminations and having a neck extending between said side laminations formed with a head extending into said notches in the side laminations.

5. In a bobbin releaser for a weft replenishing mechanism operating with a cradle, a plurality of elongated parallel sheet metal laminations certain of which form the sides of the releaser and the others of which are intermediate the side laminations, lugs on the side laminations adjacent one end of the releaser projecting beyond adjacent parts of the intermediate laminations defining a space which is central with respect to the length of the releaser between said lugs, and a cradle operating wing formed of flat metal having a neck projecting upwardly therefrom and secured to the laminations in said space with said wing disposed either to the right or the left of the releaser.

6. In a bobbin releaser for a weft replenishing mechanism operating with a cradle, a plurality of sheet metal laminations secured together arranged side by side and formed at one end of the releaser with a T-shaped recess symmetrical about a line running lengthwise of the releaser, and a cradle operating wing secured to the laminations having a T-shaped extension to fit said T-shaped recess, said wing being flat and capable of having said extension inserted into said recess with the wing disposed either to the right or to the left of the releaser.

7. In a bobbin releaser for a weft replenishing mechanism operating with a cradle, a plurality of elongated sheet metal laminations secured together and arranged side by side and formed at one end of the releaser to provide a recess running lengthwise of the releaser, and a cradle operating wing secured to the laminations having an elongated extension to fit said recess when the wing is disposed either to the right or the left of the releaser.

8. In a bobbin releaser for a weft replenishing mechanism operating with a color slide, a plural-

ity of elongated sheet metal laminations arranged side by side having aligned perforations formed therein, an operating lug having an arm extending laterally from one side of the releaser and formed with an operating finger for the color slide bent at an angle to said arm, and a tongue extending from said arm into said aligned perforations and secured to the laminations to assist in holding the latter together.

10. In a bobbin releaser for a weft replenishing mechanism operating with a color slide, a plurality of sheet metal laminations arranged side by side and having aligned slots elongated in the direction of the length of the releaser, an operating lug having an arm extending laterally from the releaser and having an operating finger for the color slide bent at an angle to the arm, a tank projecting from said arm formed to fit said slots extending into the latter through all of the laminations, and bonding metal securing said tongue and laminations to each other.

11. In a bobbin releaser for a weft replenishing mechanism operating with a setting bar, an elongated body having a recess in the upper end thereof, a dog pivoted to said upper end of the releaser formed of a piece of sheet metal having a pawl-like body for the bar, a spring receiving metallic cup, arms integral with said pawl-like body extending partly around said cup and bonded to the latter, said cup being open at the upper end and closed at the lower end thereof, and a compression spring the lower end of which extends into said cup and engages the bottom of the latter and the upper end of which extends into said recess in the releaser.

12. In a bobbin releaser for a weft replenishing mechanism operating with a setting bar, an elongated body comprising a plurality of laminations certain of which form the sides of the releaser and the others of which are intermediate the side laminations, the intermediate laminations having a recess formed therein between the side laminations, a dog for the bar pivoted to the releaser, and a compression spring operatively related at one end thereof to the dog and having the other end thereof in said recess.

13. Two bobbin releasers of opposite hand for a weft replenishing mechanism, each releaser having an elongated body, four operating offset lugs for said two releasers, a pair of said lugs being identical and of one hand and the other pair being identical but of the opposite hand, two of said lugs in high position and two in low position, one of the lugs of said first pair being attached to one of the releasers in high position on the side thereof adjacent to the other releaser and the other lug of said first pair being attached to the other releaser on the side thereof adjacent to said one releaser in low position, and one of the lugs of said other pair being attached to said one releaser in low position below said one lug of said first pair and the other lug of said other pair being attached to the other releaser in high position above said other lug of said first pair.

WILLIAM A. BLANCHARD.
